UNITED STATES PATENT OFFICE.

MARCELEAN DOLPHIN, OF NEW YORK, N. Y., ASSIGNOR OF FIFTY-ONE ONE-HUNDREDTHS TO GUSTAVUS E. STRAUSS, OF NEW YORK, N. Y.

GLOVE-SUPPORTING DEVICE.

1,264,905.

Specification of Letters Patent. Patented May 7, 1918.

Application filed November 13, 1916. Serial No. 131,066.

To all whom it may concern:

Be it known that I, MARCELEAN DOLPHIN, a citizen of the United States of America, residing at 135 West 84th street, New York, 5 in the county of New York and State of New York, have invented certain new and useful Improvements in Glove-Supporting Devices, of which the following is a specification.

This invention relates to a glove cleaning, 10 stretching and drying device, adapted to be inserted within a glove to hold the same in stretched or expanded condition.

The device is particularly useful for supporting a glove and holding the same 15 stretched after washing or cleaning, but it is also adapted to be inserted within a glove, particularly a glove of kid or undressed leather, to hold the same in proper shape and condition after the same has been worn, 20 to prevent shrinkage or contraction and wrinkling thereof.

The object of the invention is to provide a device by which the digits or fingers and thumb of the glove as well as the palm or 25 hand portion thereof will be supported in a condition which is practically the same as that which the glove assumes when in use on the hand of the wearer, the digital and palm portions of the glove being held fully 30 filled out, expanded or stretched, as in use. Another object of the invention is to provide a single device adapted to support in stretched or expanded condition, a pair of gloves, so as to prevent one of said gloves 35 becoming separated from its mate and lost after washing or cleaning, or after use thereof.

The invention is illustrated by the accompanying drawings, in which:—

40 Figure 1 shows in front elevation a device constructed according to the present invention and adapted to support a single glove,

45 Fig. 2 shows in side elevation another form of the device adapted to support a pair of gloves, the two parts of this device being substantially the same as that shown in Fig. 1,

50 Fig. 3 is an enlarged detail view of one of the digital or finger portions of the glove, and

Fig. 4 is a plan view of the digital or finger portion shown in Fig. 3.

Referring to Figs. 1 and 2 of the drawings, it will be seen that the device is formed 55 from a single piece of wire which is bent and

curved so as to form a framework having the general outline and form of a hand, such framework as illustrated consisting essentially of arm portions 1 and 2, adapted to engage the opposite sides of the arm or wrist 60 portion of a glove; palm or hand portions 3 and 4, adapted to engage opposite sides of the hand or palm portion of the glove; and digital or thumb and finger portions 5, adapted to extend into the thumb and fingers 65 of the glove.

By reference to Figs. 3 and 4, it will be noted that each of the digital portions 5 is made up of four wire portions 6, 7, 8 and 9, these several portions all being spaced from 70 each other as clearly shown in said figures, so that when the glove is supported on the framework, each digital portion 5 engages the corresponding digital portion of the glove with what may be termed a four point 75 contact throughout the entire length of said digital portions, the fingers and thumb of the glove being thus filled out, or expanded or stretched in the same manner as they would be filled out by the fingers and thumb 80 of the wearer.

In forming the framework, the wire portion 6 of the thumb or first digit forms a continuation of the palm portion 4 and the wire is then bent downwardly and upwardly 85 to form the wire portions 7 and 8, and then bent downwardly to form the wire portion 9, and again bent upwardly to form the wire portion 6 of the second digit. These operations are repeated for each digit, and the 90 palm portion 3 forms a continuation of the wire portion 9 of the last digit. The bends 10 and 11 between the portions 6 and 7 and 8 and 9 respectively are of such form that the portions 7 and 8 are spaced forwardly 95 from the portions 6 and 9, as most clearly shown in Fig. 4. While for convenience of illustration, the distance between the portions 7 and 8 is shown in Fig. 1 somewhat less than the distance between the portions 6 and 9 of the digital portions 5, it will be understood that these distances will be substantially the same, as in Fig. 4.

The wire portions 7 and 8 of the digital portions 5 may if desired be of substantially 105 the same length as the wire portions 6 and 9 as shown at 12 in Fig. 1, but it is preferable that the wire portions 7 and 8 of one or more of the digital portions of the framework be extended so as to form a palm sup- 110

porting loop or loops. In Fig. 1 two such loops are shown at 13 and 14, forming continuations or extensions of the wire portions 7 and 8 of the first and last digital portions 5. These loops are spaced forwardly from the palm or hand portions 3 and 4 of the framework, as clearly shown in Fig. 2, so that when the glove is in position on the framework, these loops serve to fill out, or 10 expand or stretch the palm or hand portion of the glove. It will thus be seen that with the formation of the digital portions 5 as above described, and by the provision of the loops 13 and 14, the glove is held by the 15 stretching or drying device after washing or cleaning, or after being worn, in practically the same condition as it assumes when in use on the hand of the wearer. Thus the appearance, shape and condition of the glove 20 are preserved and shrinkage or contraction thereof after washing or cleaning, or wrinkling or shriveling thereof after use is entirely prevented.

In the form of the device shown in Fig. 1, 25 the arm portions 1 and 2 of the framework are bent to form hook portions 15 by means of which the device may be supported from a line, chandelier, clothes hook or other convenient support or projection during drying 30 or when not in use.

The form of the device shown in Fig. 2 is adapted to support a pair of gloves. Each glove supporting portion of the device is of the form previously described in reference 35 to the single device of Fig. 1, the arm portions 4, 4 of the two glove supporting portions being continuations one of the other, the wire being bent as at 16, while the ends 40 of the wire at the terminations of the arm portions 3, 3, might be suitably bent and joined together to increase the rigidity of the framework. The double device of Fig. 2 may be hung from a line, clothes hook or other support by means of the bent portion 45 16.

The wire of which the framework is constructed may be rigid or may be slightly elastic as desired, and the digital portions and other portions of the framework may 50 be so formed as to be slightly expandable and contractible, in order to increase the expanding or stretching action of the device on the glove. Further the wire may be such that it will resist rust or tarnishing and will 55 not stain the glove supported thereon, or it may be plated or enameled or otherwise coated or covered to prevent such tarnishing or staining.

The framework may of course be made in 60 various sizes and forms to suit different sizes and kinds of gloves, and the digital portions 5 might each comprise more than four wire portions, or more than two glove supporting portions might be made from a single length of wire.

I claim:—

1. A glove supporting device which comprises a wire framework consisting of a single piece of wire bent to form a plurality of integral digital portions each comprising 70 more than two integral wire portions all spaced from each other.

2. A glove supporting device which comprises a wire framework having a plurality of digital portions each comprising four 75 integral wire portions all spaced from each other.

3. A glove supporting device which comprises a wire framework having a plurality of integral digital portions each comprising 80 a plurality of integral wire portions all spaced from each other, and having a palm supporting loop, bent outwardly to lie in a plane spaced from that of the main portion of said framework. 85

4. A glove supporting device which comprises a wire framework having a plurality of digital portions each comprising a plurality of wire portions all spaced from each other, and having a palm supporting loop 90 forming an integral continuation of the wire portions of one of said digital portions and bent outwardly to lie in a plane spaced from that of the main portion of said framework.

5. A glove supporting device which comprises a wire framework having a plurality of digital portions each comprising more than two wire portions all spaced from each other, and a plurality of palm supporting loops forming integral continuations of the 100 wire portions of certain of said digital portions. 95

6. A glove supporting device which comprises a wire framework having a plurality of digital portions each comprising four integral wire portions all spaced from each other, and having a palm supporting loop. 105

7. A glove supporting device which comprises a single piece of wire bent to form arm portions, hand portions, a plurality of 110 digital portions each comprising a plurality of wire portions all spaced from each other, and a palm supporting loop bent outwardly to lie in a plane spaced from that of the main portion of said framework. 115

8. A glove supporting device which comprises a wire framework having arm portions, hand portions, a plurality of digital portions each comprising more than two wire portions all spaced from each other, and a palm supporting loop forming an integral continuation of the wire portions of one of said digital portions. 120

9. A glove supporting device comprising a wire framework having a plurality of portions each adapted to support a glove, said glove supporting portions each consisting of a plurality of digital portions each comprising four wire portions all spaced from each other. 125

10. A glove supporting device comprising a wire framework formed from a single length of wire and consisting of a plurality of portions each adapted to support a glove, said glove supporting portions each having a plurality of digital portions each comprising a plurality of wire portions all spaced from each other.

11. A glove supporting device, comprising a wire framework consisting of a single length of wire bent to form a plurality of portions each adapted to support a glove, said glove supporting portions being arranged substantially parallel to each other and each having a plurality of digital portions, each digital portion comprising a plurality of wire portions all spaced from each other.

12. A glove supporting device which comprises a single piece of wire bent to form a plurality of digital portions each comprising

ing spaced wire portions arranged in one plane and other spaced wire portions arranged in a different plane.

13. A glove supporting device which comprises a wire framework having a plurality of digital portions each comprising a plurality of pairs of spaced wire portions.

14. A glove supporting device which comprises a wire framework having a plurality of digital portions each comprising a plurality of pairs of spaced wire portions, and a palm supporting loop forming a continuation of one pair of wire portions of one of said digital portions.

In testimony whereof I affix my signature in presence of two witnesses.

MARCELEAN DOLPHIN.
